CONTOUR REPRODUCING APPARATUS

Howard Thrasher, Long Beach, Calif., assignor
to Vultee Aircraft, Inc., Downey, Calif., a corporation of Delaware

Application July 5, 1940, Serial No. 343,976

7 Claims. (Cl. 33—25)

The present invention relates generally to apparatus for reproducing on plates or other surfaces the contours of templates. More particularly the invention relates to that type of contour reproducing apparatus which operates on the pantograph principle and comprises (1) a base with an upstanding pivot pin thereon, (2) a pair of long centrally crossed primary arms having the central portions thereof mounted on, and rotatable relatively to, the pivot pin, (3) a pair of short tracing arms extending between the ends of the primary arms that are at one side of the base and having the outer ends thereof pivotally connected to such ends of the primary arms and their inner ends pivotally connected together and provided with means for supporting a tracing tool, and (4) a pair of short scribing arms extending between the other ends of the primary arms, i. e., the ends at the other side of the base, and having their outer ends pivotally connected to the last mentioned ends of the primary arms and their inner ends pivotally connected together and provided with means for retaining a scribing tool.

One object of the invention is to provide a contour reproducing apparatus of this type which has greater capabilities of use than previously designed apparatus for the same purpose and is of such design and construction that it is extremely accurate and may be operated expeditiously.

Another object of the invention is to provide a contour reproducing apparatus of the type under consideration in which the centrally crossed primary arms are formed of tubes and embody a truss design or arrangement whereby they are so rigid that they are free from bending or deflection during use of the apparatus.

Another object of the invention is the provision in connection with a contour reproducing apparatus of the type and character under consideration of a simple and novel attachment which is adapted to be used in connection with the tracing tool and makes it possible to produce an undersized contour.

Still another object of the invention is the provision of an attachment which is adapted for connection to the tracing tool and enables the user of the apparatus to produce an oversized contour.

A further object of the invention is to provide a contour reproducing apparatus having novel forms or types of pivotal connections between the inner ends of the short tracing and scribing arms and in addition a supporting base of im-

proved design and a caster for supporting the inner ends of the scribing arms.

A still further object of the invention is to provide a contour reproducing apparatus which is generally of new and improved design and not only may be produced at a low and reasonable cost but also is especially designed and adapted for use in connection with aircraft work.

Other objects of the invention and the various advantages and characteristics of the present contour reproducing apparatus will be apparent from a consideration of the following detailed description.

The invention consists in the several novel features which are hereinafter set forth and are more particularly defined by claims at the conclusion hereof.

In the drawings which accompany and form a part of this specification or disclosure and in which like numerals of reference denote corresponding parts throughout the several views:

Figure 1 is a plan view of a contour reproducing apparatus embodying the invention;

Figure 2 is a vertical transverse section taken on the line 2—2 of Figure 1 and showing in detail the design of the supporting base and the construction and arrangement of the centrally crossed primary arms;

Figure 3 is an enlarged vertical section of the inner ends of the tracing arms, illustrating in detail the pivotal connection between such ends and showing the tool with the attachment for so controlling the apparatus that it operates to reproduce undersized contours;

Figure 4 is a horizontal section taken on the line 4—4 of Figure 3, and disclosing the construction and design of the attachment shown in Figure 3;

Figure 5 is a side view or elevation of the pivoted inner ends of the tracing arms, illustrating in detail the design and construction of the tracing tool and showing the latter with the attachment for use in connection with the reproduction of oversized contours;

Figure 6 is a horizontal section taken on the line 6—6 of Figure 5; and

Figure 7 is an enlarged vertical sectional view showing the pivotal connection between the inner ends of the scribing arms and illustrating in detail the construction and design of the scribing tool and the caster for supporting the scribing arms.

The apparatus which is shown in the drawings constitutes the preferred embodiment of the invention. It is designed and adapted to repro-

duce on a plate P the contour of a template T and comprises a supporting base 8, a pair of primary arms 9 and 10, a pair of tracing arms 11 and a pair of scribing arms 12. It is contemplated that the plate P and the template T be placed in side by side relation on top of a table or other suitable horizontal supporting surface. When the apparatus is used, as hereinbefore pointed out, it serves to scribe on the top face of the plate P the contour or outline of the template T.

The supporting base 8 is adapted to be placed on the plate P, as shown in Figure 1, or to rest on the table top. It is equilaterally triangular in shape and embodies screw type legs 13 and an upstanding pivot pin 14. The legs 13 are three in number and extend through internally threaded vertically extending holes in the corners of the base 8. By turning the legs in a clockwise or counterclockwise direction the supporting base 8 may be readily adjusted into a truly horizontal position. Preferably the upper ends of the legs are provided with knurled heads 15 so that they may be readily turned in connection with adjustment thereof. Turning of the legs in one direction operates to raise the supporting base and turning of the legs in the opposite or reverse direction results in lowering of the supporting base. The legs have longitudinally extending holes in their central portions in order to accommodate nails in the event that the user desires to nail the apparatus to the floor. The pivot pin 14 is fixedly secured to the central portion of the supporting base 8, as shown in Figure 2, and extends upwardly at right angles to the base. It is of uniform diameter from one end thereof to the other and serves, as hereinafter described, as the pivot medium for the central portions of the primary arms 9 and 10 of the apparatus.

The primary arms 9 and 10 are comparatively long, as shown in Figures 1 and 2, and are centrally crossed. They are centrally pivoted on the pivot pin 14 in order that they are free to rotate in a horizontal plane. The two arms are equal in length. The arm 9 is of truss design and consists of a hub forming vertically extending sleeve 16, a pair of short tubes 17, a pair of long centrally bowed tubes 18 and a pair of diagonal brace forming tubes 19. The hub forming sleeve 16 extends around and is rotatably mounted on the pivot pin 14 on the supporting base 8 and together with the pin forms a central pivot whereby the arm 9 is permitted to swing freely in a horizontal plane either in a clockwise or counterclockwise direction. The short tubes 17 radiate from the lower end of the sleeve 16 and are positioned one diametrically opposite the other. The inner ends of the tubes 17 are welded or otherwise rigidly secured to the lower end of the sleeve 16 and the outer ends are welded or otherwise secured to the centrally bowed portions of the long tubes 18. Said long tubes, as shown in Figures 1 and 2, extend horizontally. They are disposed in opposed relation and have the outer ends fixedly secured together. The tubes 18 radiate from the sleeve 16 and have the inner ends thereof welded or otherwise secured to the upper end of the sleeve. The outer ends of the tubes 18 are welded to the outer ends of the tubes 19. Because of the truss design or arrangement of the arm 9 the latter is rigid and is not subjected to any bending or deflection in connection with operation of the apparatus. The primary arm 10 is substantially the same in design and construction as the arm 9. It com-

prises a hub forming sleeve 20, a pair of short tubes 21, a pair of long centrally bowed tubes 22 and a pair of diagonal brace forming tubes 23. The sleeve 20 surrounds and is rotatable relatively to the sleeve 16 of the arm 9 and is held against vertical displacement with respect to the latter. The short tubes 21 are fixed to and radiate from the lower end of the sleeve 20 and are positioned one diagonally opposite the other. The long tubes 22 of the arm 10 are disposed in opposed relation and extend horizontally. The central portions of the last mentioned tubes are welded or otherwise fixedly secured to the outer ends of the tubes 21 and the outer ends of the tubes 22 are welded together as shown in Figure 1. The diagonal brace forming tubes 23 radiate from the sleeve 20 and have the inner ends thereof fixedly secured to the upper end of the sleeve. The outer ends of the tubes 23 are joined to the outer ends of the tubes 22 at the juncture points of such tubes. The sleeve 20 permits the arm 10 to rotate in a horizontal plane either clockwise or counterclockwise and also relatively to the arm 9. The tubes of which the two arms 9 and 10 are principally formed are preferably metallic tubes although tubes of other material may, if desired, be employed. By properly adjusting the screw type legs 13 of the base 8 the pivot pin 14 may be positioned perpendicular to the end that the arms 9 and 10 rotate in a truly horizontal plane.

The tracing arms 11 extend between the ends of the primary arms that are at one side of the supporting base 8. They are preferably in the form of metallic tubes and are joined at the outer ends thereof to said ends of the primary arms by pivotal connections 24, as shown in Figure 1. The inner end of each tracing arm 11 is provided with a ring shaped member 25. The two members 25 are positioned one above the other. They are coaxially arranged and surround a vertically extending tubular holder 26 for a tracing tool 27. Two ball bearings 28 extend between the ring shaped members 25 and the central portion of the holder 26 and together with the holder form a pivotal connection between the inner ends of the tracing arms 11. Said bearings are positioned one above the other and comprise inner races 29, outer races 30 and balls 31 between the inner and outer races. The inner races surround the central portion of the holder 26 and are clamped against a shoulder 32 on the upper end of the holder by means of a nut 33 on the lower end of the holder. The outer races 30 of the ball bearings 28 are pressed or otherwise fixedly secured within the inner peripheries of the ring shaped members 25. The tracing tool 27 extends vertically through the tubular holder 26 and has a socket 34 in its lower end. The upper end of the holder 26 is externally threaded and split longitudinally and has a nut 35. When this nut is tightened it contacts the upper end of the holder around the tracing tool 27 and thus locks the tool against vertical displacement relatively to the holder. The holder 26 serves to hold the tracing tool 27 so that its center line coincides with the true center of the pivotal connection which is formed between the inner ends of the tracing arms 11 by the ball bearings 28.

The scribing arms 12 extend between the ends of the primary arms that are at the opposite side of the supporting base 8 and are preferably in the form of metallic tubes. They are disposed and move in a horizontal plane and are the same in length as the tracing arms 11. The outer ends

of the scribing arms 12 are joined by the adjoining or adjacent ends of the primary arms by pivotal connections 36. The inner end of each of the arms 12 is provided with a ring shaped member 37. The two members 37 are positioned one above the other and surround a vertically extending tubular holder 38 for a scribing tool 39. Two ball bearings 40 are interposed between the central portion of the holder 38 and the ring shaped member 37 and together with the holder form a pivotal connection between the inner ends of the scribing arms 12. The inner races of the ball bearings are clamped against a shoulder 41 at the upper end of the holder by means of a nut 42 on the lower end of the holder. The scribing tool 39 fits slidably in the holder 38 and has a pointed lower end for scribing purposes. Weights are mounted on the upper end of the tool 39 and serve to urge the point of the tool into contact with the plate P. By removing or adding weights the tool may be properly weighted. Because of the design or arrangement and pivotal connection of the primary, tracing and scribing arms the scribing tool 39 is caused during movement of the tracing tool 27 to move conformably or correspondingly to the tracing tool. When the pointed end of the scribing tool 39 is on the top face of the plate P and the tracing tool 27 is moved around the edge or periphery of the template T the scribing tool marks or scribes on the top surface of the plate P the contour of the template. If the tracing tool 27 is moved around the template T at a fixed distance inwardly of the edge of the template the contour which is formed by the scribing tool 39 on the plate P will be of sub or undersize. If the tracing tool is moved around the template at a fixed distance outwardly of the edge of the template the contour on the plate T will be oversized.

In addition to the parts heretofore described or recited the apparatus comprises a tracing attachment 44 for use in making undersized contours and a tracing tool attachment 45 for use in making oversized contours.

The attachment 44 (see Figures 3 and 4) comprises a plate 46 in the shape of a quadrant, an upstanding connecting pin 47 on the inner corner of the plate 46 and a template engaging roller 48 beneath the plate. The pin 47 is adapted to fit snugly within the socket 34 at the lower end of the tracing tool 27 and serves when in place in the socket to connect the plate 46 of the attachment 44 fixedly to the tracing tool. The roller 48 is adapted to engage and travel along the edge of the template T, as shown in Figure 4. It is located under the central portion of the plate 46 and it serves, as hereinafter described, to hold the scribing tool 27 a predetermined distance inwardly of the edge of the template. It is mounted rotatably on the lower end of a pin 49. This pin extends through an arcuate slot 50 in the central portion of the plate 46 and it is connected to, and depends from, the small end of a bell crank type lever 51. The lever is mounted over the plate 46 and has a pivotal connection 52 between its central portion and the plate. The long end of the lever projects in the direction of the curved edge of the plate and substantially radially with respect to the connecting pin 47. The pivotal connection 52 is located at the center of the arcuate slot 50. Because of the position of the roller 48 the roller serves to hold the tracing tool 27 at a predetermined distance inwardly of the edge of the template when the roller is in contacting re-

lation with the edge of the template. When the attachment 44 is in place and the tracing tool 27 is moved so as to cause the roller 48 to move around the edge of the template the scribing tool 39 scribes or marks an undersized contour on the plate P. Because of the manner in which the roller 48 is mounted the distance between the roller and tracing tool may be varied in order to adjust or change the amount of undersize of the scribed contour. When the lever 51 is moved in a counterclockwise direction, as viewed in Figure 4, the roller 48 and the tracing tool are moved apart and this results in a contour of large undersize. When the lever 51 is swung in a clockwise direction, as viewed in Figure 4, the roller and tracing tool are moved together with the result that the amount of undersize as far as the scribed contour is concerned is a minimum. By adjusting the position of the roller with respect to the tracing tool any desired amount of undersize may be obtained as far as the scribed contour is concerned. The size of the slot 50 is such that when the lever 51 is swung clockwise to the fullest extent the center line of the tracing tool 27 is in alignment with the periphery of the roller 48. When the tool 27 is positioned so that the center line thereof is in alignment with the periphery of the roller and the roller is moved around the edge of the template the scribing tool 39 makes or scribes a contour which is exactly the same in size and shape as the template. The outer end of the long arm of the bell crank lever 51 is in the form of a pointer and this coacts with a scale 53 on the curved margin of the plate 46 to indicate the distance between the roller and the tracing tool 27. When it is desired to use the contour reproducing apparatus without the attachment 44 it is only necessary to raise the tracing tool 27 or lower the attachment 44. Either operation results in disconnection of the attachment from the tracing tool.

The attachment 45 for use in making oversized contours comprises a connecting pin and a roller. The roller is rotatably mounted on the lower end of the pin. The pin is adapted to fit within the socket 34 in the lower end of the tracing tool 27 and serves to hold the attachment 45 in connected relation with said tool 27. The roller is adapted to contact with the edge of the template T and serves to hold the tracing tool a predetermined distance outwardly of the edge of the template. When the roller is in contact with the edge of the template and the tracing tool is moved around the template the scribing tool 39 scribes an oversized contour on the plate P. By substituting rollers of different diameter for the rollers of the attachment 45 the attachment may be made to effect any desired amount of oversize as far as the scribed contour is concerned. When it is desired to remove the attachment 45 it is only necessary to withdraw the connecting pin from the socket 34.

In order to hold the holder 38 for the scribing tool 39 at a fixed distance with respect to the plate P in connection with a contour reproducing operation a caster 54 is provided. This caster is connected by a pair of opposed clamp brackets 55 to the inner end of one of the scribing arms 12. During a contour reproducing operation the caster rolls over the top face of the plate P and holds the holder 38 at a fixed distance above the plate. The caster, as shown in Figure 7, comprises a roller 56 and a vertically extending pivot pin 57. The lower end of the pivot pin is bent at right angles and serves as a hub for the

central portion of the roller. The upper end of the pivot pin extends through aligned holes in the clamp brackets 55 in order that the caster 54 is free to swivel or rotate about the axis of the pin. The clamp brackets have bolts 58 for clamping them together and embody any suitable means for preventing axial or vertical displacement of the pivot pin relatively thereto.

The herein described contour reproducing apparatus is essentially a precision instrument because of the truss arrangement or design of the primary arms 9 and 10. It may be manufactured at a comparatively low and reasonable cost and is characterized by the fact that the attachments 44 and 45 enable the user to make either undersized or oversized contours. By reason of the two attachments the apparatus has particular utility in connection with aircraft work where great precision and accuracy are called for. In the apparatus which is shown in the drawings the primary arms are pivotally connected at their centers and are twice as long as the tracing and scribing arms. Because of this the apparatus has a 1 to 1 ratio. By changing the pivot pin for the primary arms and lengthening or shortening the scribing arms 12 the ratio of the apparatus may be changed.

The invention is not to be understood as restricted to the details set forth since these may be modified within the scope of the appended claims without departing from the spirit and scope of the invention.

Having thus described the invention what I claim as new and desire to secure by Letters Patent is:

1. An apparatus adapted to reproduce contours of templates and comprising a base having an upstanding pivot pin thereon, a pair of horizontally disposed centrally crossed rotatable truss-type primary arms each embodying a hub-forming sleeve mounted rotatably about the pin, a pair of short horizontal members connected to, and extending radially in opposite directions from, the sleeve, and a pair of horizontally extending opposed centrally bowed members having the central portions thereof fixedly connected to the outer ends of the short members respectively and their ends connected together, a pair of tracing arms extending between the ends of the primary arms that are at one side of the base and having the outer ends thereof pivotally connected to such ends of the primary arms and their inner ends pivotally connected together and provided with means for supporting a tracing tool, and a pair of scribing arms extending between the other ends of the primary arms and having their outer ends pivotally connected to said other ends of the primary arms and their inner ends pivotally connected together and provided with means for retaining a scribing tool.

2. An apparatus adapted to reproduce contours of templates and comprising a base having an upstanding pivot pin thereon, a pair of horizontally disposed centrally crossed, rotatable, truss-type primary arms each embodying a vertically extending hub-forming sleeve mounted rotatably about the pin, a pair of short horizontally extending tubes welded to, and extending radially in opposite directions from, the sleeve, and a pair of comparatively long horizontally extending opposed centrally bowed tubes having the central parts thereof welded to the outer ends of the short tubes and their ends welded together, a pair of tracing arms extending between the ends of the primary arms that are at one

side of the base and having the outer ends thereof pivotally connected to such ends of the primary arms and their inner ends pivotally connected together and provided with means for supporting a tracing tool, and a pair of scribing arms extending between the other ends of the primary arms and having their outer ends pivotally connected to said other ends of the primary arms and their inner ends pivotally connected together and provided with means for retaining a scribing tool.

3. An apparatus adapted to reproduce contours of templates and comprising a base with an upstanding pivot pin thereon, a pair of comparatively long, horizontally disposed, rotatable, centrally crossed, truss-type primary arms each consisting of a vertically extending hub-forming sleeve mounted rotatably about the pin, a pair of short horizontally extending members connected to and extending radially in opposite directions from, the lower end of the sleeve, a pair of comparatively long horizontally extending opposed centrally bowed members having the central parts thereof fixedly connected to the outer ends of the short members and their outer ends fixedly secured together, and a pair of diagonal oppositely extending brace forming members connected to, and projecting outwardly in opposite directions from, the upper end of the sleeve and having the outer ends thereof connected to the ends of the centrally bowed members, a pair of short tracing arms extending between the ends of the primary arms that are at one side of the base and having the outer ends thereof pivotally connected to such ends of the primary arms and their inner ends pivotally connected together and provided with means for retaining a scribing tool.

4. An apparatus adapted to reproduce contours of templates and comprising a base having an upstanding pivot pin, a pair of horizontally disposed centrally crossed rotatable truss-type primary arms, one of said arms consisting of a vertical hub forming sleeve mounted rotatably on the pivot pin, a pair of horizontally extending opposed centrally bowed members having the central portions thereof fixed to the lower portion of the sleeve, and a pair of diagonal brace members connected to, and extending in opposite directions from, the upper end of said sleeve and having the outer ends thereof connected to the ends of said centrally bowed members, the other primary arm being the same in design and construction as said one arm but having the sleeve thereof rotatably mounted on the sleeve of said one arm and having its centrally bowed members and its diagonal brace members overlying and underlying the centrally bowed members and the diagonal brace members of said one arm respectively, a pair of tracing arms extending between the ends of the primary arms that are at one side of the base and having the outer ends thereof pivotally connected to such ends of the primary arms and their inner ends pivotally connected together and provided with means for supporting a tracing tool, and a pair of scribing arms extending between the other ends of the primary arms and having their outer ends pivotally connected to said other ends of the primary arms and their inner ends pivotally connected together and provided with means for retaining a scribing tool.

mary arms and their inner ends pivotally connected together and provided with means for retaining a scribing tool.

5. An apparatus adapted to reproduce the contour of a template and comprising a pair of centrally crossed primary arms pivotally connected together at the point of crossing, a pair of tracing arms extending between certain of the ends of the primary arms and having the outer ends thereof pivotally connected to said certain ends and their inner ends secured together by a pivotal connection, a holder forming a part of, and disposed centrally with respect to, the pivotal connection, a tracing tool adapted to engage and be moved around the edge of the template and having mounting means between it and the holder whereby it is laterally adjustable to and from the center point of said pivotal connection, and a pair of scribing arms extending between the other ends of the primary arms and having the outer ends thereof pivotally connected to said other ends and their inner ends pivotally connected together and provided with means for retaining a scribing tool.

6. An apparatus adapted to reproduce the contour of a template and comprising a pair of centrally crossed primary arms pivotally connected together at the point of crossing, a pair of tracing arms extending between certain of the ends of the primary arms and having the outer ends thereof pivotally connected to said certain ends and their inner ends secured together by a pivotal connection, a holder forming a part of, and disposed centrally with respect to, the pivotal connection, a roller disposed outwardly of, the 35

holder and adapted to engage and be moved around the edge of the template, means between the roller and holder for supporting said roller so that it is adjustable laterally to and from the center point of said pivotal connection, and a pair of scribing arms extending between the other ends of the primary arms and having the outer ends thereof pivotally connected to said other ends and their inner ends pivotally connected together and provided with means for retaining a scribing tool.

10 7. An apparatus adapted to reproduce the contour of a template and comprising a pair of centrally crossed primary arms pivotally connected together at the point of crossing, a pair of tracing arms extending between certain of the ends of the primary arms and having the outer ends thereof pivotally connected to said certain ends and their inner ends secured together by a pivotal connection, a holder forming a part of, and disposed centrally with respect to, said connection, a roller adapted to engage and be moved around the edge of the template, supporting means for the roller including a bell crank type lever between said roller and the holder whereby the roller is laterally adjustable to and from the center point of said pivotal connection, and a pair of scribing arms extending between the other ends of the primary arms and having the outer ends thereof pivotally connected to said other ends and their inner ends pivotally connected together and provided with means for retaining a scribing tool.

HOWARD THRASHER.
